HINGE

John F. Voelkel, Brooklyn, N. Y., assignor to John F. Voelkel and Chas. F. Gehrman, executors of the estate of Emil Bommer, deceased, doing business as Bommer Spring Hinge Company, Brooklyn, N. Y.

Application May 13, 1940, Serial No. 334,780

3 Claims. (Cl. 16—153)

This invention relates to hinges, and more particularly to shielded hinges.

The object of this invention is to provide a shielded hinge which may be easily inserted into a door without the necessity of complicated boring, insertion of screws and the like.

For this purpose the invention consists of a shielding casing having a bifurcated slot therein for the passage of a stem engaging a cylindrical portion so that upon the ascent and descent of the door, as is customary with hinges of this type, the parts are concealed as much as possible.

The invention will be more fully described hereinafter, embodiments thereof pointed out in the drawings, and the invention will be finally set forth in the claims.

In the accompanying drawings:

Figure 1 is a partial side view of a door and door casing with the improved hinge applied thereto;

Figure 2 is a section taken on line 2—2 of Figure 1;

Figure 3 is a horizontal section taken on line 3—3 of Figure 1;

Figure 4 is a side view of the internal cylindrical portion having the cutout;

Figure 5 is a side view partially in section of the stem upon which the device shown in Figure 4 rests;

Figure 6 is an enlarged view in section of the parts shown in Figure 1, taken on the line 6—6 of Figure 2;

Figure 7 is a side view showing the detail of the cam stem;

Figure 8 is a top view of Figure 7; and

Figure 9 is a sectional end view of the casing, taken on the line 9—9 of Figure 6.

Similar characters of reference indicate corresponding parts throughout the various views.

Referring to the drawings, and more particularly to Figure 1, the usual door casing 10 has supported thereon a door 11 by means of the hinges generally indicated by 12 and 13. It is a desire in hinges of this kind to have the exterior

casing made of chrome plated metal, and preferably to have it of continuous contour, i. e., shielded or the like, so that a barrel casing of the hinge from the exterior appears the same no matter in what position the hinge is placed. For instance, the casing of the hinge 13 is cylindrical and chrome plated at its exterior and makes a very pleasing appearance, and in consequence it is the desire of users of hinges to have the upper hinge 12 present substantially the same appearance. It has heretofore been proposed to have

the casing of the upper hinge of one uniform metal cylinder, i. e., shielded, but it has been found that when devices of that kind were applied to the door it was necessary to cut out from the top of the door recesses in the door structure and bores in the door itself to enable screws to pass through, which screws were to hold the improved hinge. Other deficiencies of installation are attendant that type of hinge.

This invention overcomes these objections by reason of the fact that a short distance below the top of the door a simple recess is cut out as indicated by the line 15 in Figure 6; and into this recess there is then inserted the internal cylinder 16 and the external cylinder 17. The external cylinder 17 has two rearwardly extending flanges 18 and 19 having openings 20 therein in registration with each other, and screws 21 and 22 are then inserted past these openings 20 so as to enter the sleeve 23 of the bore 24 of the door 20.

When these screws are thus inserted to engage into the openings 20 of these rearwardly extending ears 18 and 19, the internal cylinder 16 and external cylinder 17 are held in position in the recess 15 of the door. The fastening to the door casing is equally simple, in that an L-shaped member 25 has an opening 26, and this L-shaped member 25 has a cutout 27 in which is seated an extending portion 28 of a member 29 having a bore 30. Screws 31 and 32 pass through the openings 26 and 30, and entering the sleeve 34 which is seated in the bore 35, secure these plates 25 and 29 in position. To the plate 25 is secured a stem 36 which has an annulus 37, in the opening 38 of which the vertical shaft member 40 enters. The shaft member 40 as shown in Figure 5 is made integral with a disc member 41 having an inset portion 42 of concentric circumference, and upon the inset portion 42 the internal cylinder 16 is seated, which internal cylinder 16 has the opening 43 for the passage of the stem 36.

The door 11 when moved on its hinges causes the shaft 40 to rotate within the annulus 37, but as the door raises itself it is necessary for the outer casing 17 to have an inclined slot which is indicated in Figure 1 by the character 50 and extends from the inside of the door downwardly on both sides thereof. Thus, as the door 11 swings and is raised, the exterior cylinder 17 has the upper part of its slot right upon the stem 36, and when the door is moved in the opposite direction, the same ascent takes place and the upper wall forming the upper part of the slot rides upon the stem 36 until the movement of the door 55.

is limited by the extreme end of the slot indicated by 51.

It will thus be seen that the exterior cylinder 17 at the exterior thereof is of a smooth surface appearance such as shown in Figure 1, and appears to be an entire and uncut cylinder save only for the slot 50. The walls 17 of the external cylinder forming this slot are curved as shown in dotted lines in Figure 6 at 52, and thereby present a very pleasing appearance, such grooving or beveling adding to the effect of the hinge. The external cylinder 17 at the edge of the door facing the door casing is slightly pointed at the slot portion at the lower part of the slot, and has a slight curvature at the upper part of the slot acting as a seat which rests upon the stem 36. The formation of this seat serves to hold the door in neutral position, i. e., in alignment with the door casing. Thus when the door is moved the cylinder may be moved to that position where the exterior end of the slot engages the stem 36, at which point the door takes a position at right angles to the door casing.

It will thus be seen that a very agreeable looking device has been produced by means of the mechanism proposed, namely, the inner base member 41 with its shaft 40 being secured to the external cylinder 17, said shaft member 40 being surrounded by the annulus 37 having the opening 38, the annulus 37 being held by the stem 36 to the ears 25 and 29 secured to the door casing. The internal cylinder 16 is freely rotatable within the cylinder 17 and has a vertical slot 50a for the stem 36. The cylinder 16 serves to close all parts of the slot 50 which are not occupied by the stem portion 36. Thereby, a shielded hinge is obtained permitting vertical and horizontal rotary movements.

As before stated, a device of the kind described may be readily inserted in a door by merely cutting out a recess 15, and then applying the ears to the door by means of screws, such as 21, 22, 31 and 32.

It will be noted that the improved hinge forming the basis of this invention is applied near the top 55 of the door, and the other hinge at 13 is likewise applied at the bottom of the door.

The other hinge will be briefly described for the sake of completeness, but forms no part of this invention, it being well known.

As shown in Figure 6, a cylindrical hollow casing 60 has a displaceable cap 61 held thereon by screws 62, and has a lug portion 63 having openings for the passage of screws 64 by means of which the hinge 13 can be readily applied to the door 11 at the bottom edge of the door. The door is provided with a cutout or recess 65 into which seats a hub portion 66 which is made integral with the cylindrical casing 60. Within the casing 60 there is a centrally disposed shaft 68 shown in Figure 7 which has secured thereto a cam member 69 having an inclined cam surface 70. This shaft has a screw threaded lower end 71 which passes through the supporting ear 73 shown in Figure 6, this lower end 71 and ear 73 being locked together with a nut and washer 73a, and which supporting ear 73 is held by two parallel members 74 and 75, shown in Figure 3, to the door casing 10 by means of the screws 76 and 77. These members are again formed in the same manner as the members 25 and 29, the member 74 being L-shaped, having a recess 78 into which a depending flange 79 of the member 75 fits. The lower end of the shaft 68 is knurled, as indicated by 80 in Figure 7, so as to

have this knurled portion engage the seat 81 of the ear 73, as shown in Figure 6, in such a manner that there is no relative rotation between the parts. A roller 82 is provided within the casing 60, which seats upon a shaft stem 83 so that the roller can rotate in respect thereto, the shaft stem 83 having the screw threaded end 84 seated within the screw threaded bore 85 of a central shaft 86 which has its subcaliber stem 87 knurled at its exterior so as to engage within the hub 66, the lower part of the shaft below 86 being free of but fitting within the hollow shaft 68 and also inside of the cam member 69.

Thus, as the door is moved, the shaft 86 is moved thereby, and this movement is in turn transmitted to the roller 82 carried by the shaft 86. The roller 82 rests in a correspondingly shaped groove of the cam member surface at 90, and by a frictional action causes the roller 82 to revolve and ride upward upon the grooved cam member surface at 70 and towards the top 91 thereof, depending upon the extent to which the door is opened. This roller 82, being fixedly secured to the casing 60 and to the door, but being free of the cam member 69 and shaft 68 which are fixedly attached to the casing 10, causes the casing 60 with the door attached to raise itself, the shaft 68 remaining permanently stationary, being fixedly attached to the casing 10 by the supporting ear 73 and the parallel members 74 and 75. Similarly if the movement takes place in the opposite direction. After the door has been raised in either direction, gravity action upon the door causes it to descend along the cam member 70 and returns the door to its initial position, it being held by the rear portion 50a of the slot 50 of the upper hinge, as shown in Figure 9, and by the resting of the roller 82 in the groove of the surface cam member 69 at 90 in the lower hinge.

It is obvious that various changes and modifications may be made in the details of construction and design of the above specifically described embodiments of this invention without departing from the spirit thereof, such changes and modifications being restricted only by the scope of the following claims.

What is claimed is:

1. In a swinging door hinge, a leaf adapted to be secured to a door casing, a stem on said leaf, an exterior cylinder mounted on a swinging door, said cylinder having a bifurcated slot therein for the passage of said stem, an inner cylinder coaxial with said exterior cylinder and having a slot for the passage of said stem, a vertical pintle mounted in said cylinders, and an annulus on the free end of said stem embracing said pintle, the inner cylinder being rotatable within the exterior cylinder to close all that portion of the bifurcated slot adjacent the sides of said stem.

2. In a swinging door hinge, a cylindrical member adapted to be secured to and be movable with a swinging door, and having a slot inclined to the horizontal and a central pintle for said member, combined with an interior cylindrical member having a vertical slot and adapted to be seated within the first cylinder, and rotatable in respect thereto, and a stem adapted to be secured to the door casing and having means engaging said pintle, said stem passing through both of the slots.

3. In a swinging door hinge, a cylindrical member adapted to be secured to and be movable with a swinging door, and having a slot in-

clined to the horizontal and a central pintle for said member, combined with an interior cylindrical member having a vertical slot and adapted to be seated within the first cylinder, and rotatable in respect thereto, and a stem adapted to be secured to the door casing and passing through both of the slots, said stem having means engaging said pintle, the interior

cylinder covering the opening of the slot of the exterior cylinder excepting where the stem closes said slot, and the slot walls being bevelled, the exterior surfaces of the interior and exterior cylinders being of polished chromium-like plating, and the cylinders enclosing the hinge members.
